TRUSTEE, OF CARLISLE, PENNSYLVANIA.

BATTERY-GRID.

1,323,720.

Specification of Letters Patent.

Patented Dec. 2, 1919.

Application filed March 6, 1915, Serial No. 12,582. Renewed April 26, 1919. Serial No. 293,017.

To all whom it may concern:

Be it known that I, FRANCIS A. POCOCK, a citizen of the United States, residing at Philadelphia, in the county of Philadelphia and State of Pennsylvania, have invented 5 certain new and useful Improvements in Battery-Grids, of which the following is a specification, reference being had therein to the accompanying drawing.

10 The object of the invention is to provide an improved grid for storage batteries, especially those of the lead-lead type, having great strength and yet at the same time having a minimum volume and weight of metal 15 and a maximum metallic surface.

Of the accompanying drawing,

Figure 1 is a side view of a grid embodying the invention.

20 Fig. 2 is a sectional view taken along the line 2—2 of Fig. 1.

Fig. 3 is a sectional view taken along the line 3—3 of Fig. 1.

Fig. 4 is a fragmentary sectional view taken along the line 4—4 of Fig. 2.

25 Fig. 5 is a fragmentary sectional view taken along the line 5—5 of Fig. 1.

Fig. 6 is a view showing one of the elements of one of the molds by means of which the grid shown in Figs. 1 to 5 may be cast.

30 Fig. 7 is a side view of a modified form of grid embodying the invention.

Fig. 8 is a sectional view taken along the line 8—8 of Fig. 7.

35 Fig. 9 is a fragmentary sectional view taken along the line 9—9 of Fig. 7.

Fig. 10 is a fragmentary perspective view of a part of the grid shown in Figs. 7 to 9.

Referring to the drawings, and especially 40 to Figs. 1 to 6, 1 represents the grid as a whole which is cast in one piece, preferably from pure lead. It is formed with an exterior frame 2 having an enlargement at 3 by means of which the conductor terminal can be attached. As shown in Figs. 2 and 5, the 45 grid is provided with two side parts which are separated from each other. The two side parts are similar, but are oppositely faced so as to provide smooth outer surfaces. Each side part is checkered, the parallelograms 50 which are provided being preferably rectangular, as shown. By referring to Fig. 1 it will be observed that each alternate parallelogram on each side part is entirely cut away to provide an aperture which is entirely unobstructed. The two side parts are

so arranged relatively to each other that the apertured parallelograms of one of them are respectively out of transverse register with the apertured parallelograms of the other of them. Each parallelogram other than those already described is occupied by two pairs of parallel bars 4, 4, which intersect each other near the corners of the parallelogram. Preferably the bars are spaced inward from the edges of the parallelograms as clearly shown in Fig. 1. Each bar is preferably triangular in cross section, as indicated in Fig. 5, one face of the triangle being outermost. It will be observed that the metal of each barred parallelogram has, at the surface, only point contact with the metal of the diagonally adjacent parallelograms. However, immediately beneath each point of contact there is provided a transverse connector 5 which varies in cross section throughout its length from one side part to the other. As shown in Fig. 2, each connector 5 is wedge-shaped along one transverse plane; and, as shown in Fig. 3, it is also wedge-shaped along another transverse plane at 70 right angles to the first, the point of the second wedge, however, being on the opposite side from the point of the first wedge.

Inasmuch as these two wedge-shaped sections intersect each other, the connector 5 75 has at its center a rectangular cross section, as shown in Fig. 4.

The construction of the grid shown in Figs. 1 to 5 will be more clearly understood 80 from a reference to Fig. 6, which shows one of the elements of one of the mold elements by means of which the grid is cast. It will be understood that a complete mold section, of which there are two, is made up of a series 85 of blocks such as that shown in Fig. 6, these being mounted on a suitable carrier in checkered arrangement with their corners engaging each other. It will be seen that each block is, basically, a parallelepipedon preferably a cube. In the outer face of each cube, and preferably slightly back from the edges, there are cut two pairs of parallel grooves 6, 6 and the corners of the cubes are cut away as indicated at 7, 7. It will be understood that when the two mold sections 90 are fitted together to form a complete mold for the grid, the substantially cubical elements of one fit between those of the other leaving as casting space only the grooves 6, 6, and the corner notches 7, 7. It will be 95 100 105 110

understood that, in casting, the grooves 6, 6 provide for the bars 4, 4 shown in Figs. 1 to 5, and that the notches 7 of four adjacent blocks provide for the transverse connectors 5 to 5.

In Figs. 7 to 10 I have shown an alternate form of grid which is especially adapted for use when a relatively thin grid can be employed. In practice, I have found it desirable to use the thicker grid shown in Figs. 1 to 5 for the positive plate of the battery and to use the thinner grid shown in Figs. 7 to 10 for the negative plate of the battery.

The alternate construction has a frame 2^a with an enlargement 3^a, these parts being similar to those already described. Like the other construction, this plate has two separated side parts each having parallelograms in checkered arrangement. Each alternate parallelogram is entirely open and unobstructed, the unobstructed parallelograms on the front side being indicated by *a* in Fig. 7, and the other parallelograms on the front side being indicated by *b*. The construction differs from that of Figs. 1 to 5 chiefly by the omission of two of the bars from each of the parallelograms *b*. It will be observed that in each of the parallelograms *b* there are provided on the front side of the plate two bars 4^a which intersect each other, instead of four bars as in the other construction; and that in each of the non-opposite parallelograms on the back side of the plate there are provided two bars 4^b which intersect each other, instead of four bars as in the other construction.

Connectors 5^a are provided between the two side parts of the grid, these being similar to the connectors 5 of the other construction. It will be observed that there are a number of points of intersection at which there are bars on but one side of the grid. At these points there are provided projections 5^b which extend entirely across the grid and are similar to the connectors 5^a. Like the connectors, they vary in cross section throughout their length. One of them is shown in perspective in Fig. 10.

I am aware that it has been heretofore proposed to provide battery grids with separated side parts and transverse connectors between them. However, I believe myself to have been the first to position the connectors at the corners of the parallelograms or rectangles, thus making but a small number of connectors necessary. With the arrangement which I have shown it will be observed that each connector serves to support the corners of two barred parallelograms, thus doing double duty. By my construction I have provided an extremely large volume for the reception of paste and have at the same time maintained the strength of the grid and have provided a large surface

area of metal. Each alternate parallelogram at each side of the grid is entirely cut away, and the space thus provided extends entirely through to the other side of the grid, except for the small space occupied by the bars 4, 4 and parts of the connectors 5, 5 at the said opposite side. Therefore, the space available for paste can be considered as made up of a series of substantially parallelepipedal spaces joining each other at their edges, each alternate one at each side of the grid being cut away to conform to the bars and the connectors. This arrangement not only provides a maximum space for paste but also provides a very great metal surface, as each of the bars 4 is exposed to the paste on two inner faces, and as the connectors 5 are exposed on all sides. The shape of these connectors not only gives them a great surface area but also enables them to firmly hold the paste. As stated, each of the connectors varies in cross section from one side of the grid to the other, and therefore there is no possibility for the paste, after hardening, to slide longitudinally of the connector.

In the construction shown in Figs. 7 to 10 the amount of space available is even greater, relatively, than in the construction shown in Figs. 1 to 5. As stated, this form of grid is especially adapted to form a negative battery plate, as with a negative plate there is less tendency for the paste to become loosened. On each surface there are relatively large areas without extended metallic connections, but these are firmly held in place by the transverse members 5^b which are so shaped that the paste is firmly gripped after it once hardens around them.

What I claim is:

1. A battery grid having in each side parallelogrammic apertures in checkered arrangement with their corners coinciding, the apertures in one side being out of transverse register with those of the other side.

2. A battery grid having substantially parallelepipedal spaces extending from one side to the other, the said spaces being in checkered arrangement with their corners coinciding and being unobstructed except at their corners and at points immediately adjacent the second said side of the grid.

3. A battery grid having substantially parallelepipedal spaces extending from one side to the other, the said spaces being in checkered arrangement with their corners coinciding and being unobstructed except at their corners and at points immediately adjacent the second said side of the grid, and having other substantially parallelepipedal spaces extending from the second said side to the first said side, the said spaces being unobstructed except at their corners and at points immediately adjacent the first said side.

4. A battery grid having substantially

- parallelepipedonal spaces extending from one side to the other, the said spaces being in checkered arrangement with their corners coinciding, and having other substantially 5 parallelepipedonal spaces extending from the second said side to the first said side, the said grid comprising bars obstructing the first said spaces at the second said side of the grid and bars obstructing the second said 10 spaces at the first said side of the grids, the said spaces being otherwise unobstructed except at their corners.
5. A battery grid having substantially parallelepipedonal spaces extending from one side to the other, the said spaces being in checkered arrangement with their corners coinciding, and having other substantially 15 parallelepipedonal spaces extending from the second said side to the first said side, the said grid comprising bars obstructing the first said spaces at the second said side of the grid and bars obstructing the second said 20 spaces at the first said side of the grids, each of the said bars being triangular in cross section with one face outermost, the said spaces being otherwise unobstructed except at their corners.
6. A battery grid having substantially parallelepipedonal spaces extending from one side to the other, the said spaces being in checkered arrangement with their corners coinciding, and having other substantially 25 parallelepipedonal spaces extending from the second said side to the first said side, the said grid comprising four parallelogrammically arranged bars obstructing each of the first said spaces at the second said side of the grid, four parallelogrammically arranged bars obstructing each of the second said spaces at the first said side of the grids, and transverse connectors with the first said bars and the second said bars at the corners of the said spaces, the said spaces being unobstructed except for the said bars 30 and connectors.
7. A battery grid formed with two similar separated side parts, each divided into parallelograms in checkered arrangement with their corners coinciding, each alternate 35 parallelogram being in the form of an entirely unobstructed aperture, and the apertured parallelograms of the two side parts being out of transverse register with each other.
8. A battery grid formed with two similar separated side parts, each divided into parallelograms in checkered arrangement with their corners coinciding and each having two pairs of parallel bars at angles to each other in each alternate parallelogram 40 and having each other parallelogram in the form of an entirely unobstructed aperture, the barred parallelograms of one side part being respectively opposite the apertured parallelograms of the other side part.
9. A battery grid formed with two similar separated side parts, each divided into parallelograms in checkered arrangement with their corners coinciding and each having two pairs of parallel bars at angles to each other in each alternate parallelogram 45 and spaced from the edges thereof and having each other parallelogram in the form of an entirely unobstructed aperture, the barred parallelograms of one side part being respectively opposite the apertured parallelograms of the other side part.
10. A battery grid formed with two similar separated side parts, each divided into parallelograms in checkered arrangement 50 with their corners coinciding and each having two pairs of parallel bars at angles to each other in each alternate parallelogram and having each other parallelogram in the form of an entirely unobstructed aperture, the barred parallelograms of one side part being respectively opposite the apertured parallelograms of the other side part, and transverse connectors between the two side parts positioned at the corners of the barred 55 parallelograms.
11. A battery grid formed with two similar separated side parts, each divided into parallelograms in checkered arrangement 60 with their corners coinciding, each alternate parallelogram being in the form of an entirely unobstructed aperture, and the apertured parallelograms of the two side parts being out of transverse register with each other, and transverse connectors between the two side parts positioned adjacent the corners of the parallelograms and each varying in cross section from one side part to the other.
- In testimony whereof, I affix my signature, 65 in presence of two witnesses.
